DEVICE FOR FORMING PORTS IN
THIN-WALLED TUBES

Felix Alexandrovich Seravin and Andrei Nikolaevich Maklakov, both of Voronezh, U.S.S.R., assignors to Experimentalny Nauchno-Issledovatel'sky Institute Kuznechno-Pressovogo Mashinostroeniya, Voronezh, U.S.S.R.

Filed May 14, 1964, Ser. No. 367,367
4 Claims. (Cl. 83—181)

This invention relates to devices for forming ports in thin-walled tubes, and more particularly to devices for forming ports in thin-walled tubes by a nibbling or punching operation.

The known devices for punching ports in tubes comprise a mandrel-die arranged on a stationary quill, a punch mounted on a press side, automatic means for rotating and moving lengthwise the tube by one step. The means for longitudinally moving and rotating the tube comprises vertical racks secured with the press slide to cooperate with a horizontal rack coupled to a hooked lever.

A hole is punched in the tube during the down stroke of the press slide, and during the upward stroke of the slide, the tube is rotated by the hooked lever, the free end of which drops into one of the punched holes. During the rotation of the tube, the hooked lever is actuated to move laterally as a result of which the tube is simultaneously shifted in the longitudinal direction.

The known devices have the drawback that a single punch is adapted to produce holes of identical size, several holes being produced, wherever required, with equal spacing.

An object of the present invention is to provide a device for producing ports in thin-walled tubes, a single punch being utilized for nibbling holes of variable size.

Another object of the present invention is to provide a device of the type permitting generation of ports in variable spaced relationship to each other in the tube treated.

A further object of the invention is to provide a device of the above-mentioned type to produce ports in thin-walled tubes by an automatic process.

Still another object of the present invention is to provide a device for producing ports in thin-walled tubes, said device ensuring very close tolerances in the punched holes and their spaced relationship in a more efficient manner than heretofore known.

In view of the above and other objects, the present invention contemplates the provision of a device for generating ports in thin-walled tubes comprising a slide-mounted punch, slide actuating means, a mandrel die, means for longitudinally moving and rotating the tube treated, and a programming unit for insuring the movement of the tube through predetermined distances, the punch according to the present invention having a cross-section corresponding to the size of the smallest port to be formed in the tube.

The slide-actuating mechanism includes means for causing the slide to assume a non-operating position without being stopped, said means comprising a wedge cooperating with a spring-urged support coupled to said mechanism and actuated by a power cylinder mounted on the frame of the device.

The mechanisms used for longitudinally moving and turning the tube are provided with motors comprising hydraulic boosters that amplify the torque and are controlled by servomotors.

The device further comprises means for synchronizing the operation of said mechanism for longitudinally moving and turning the tube, and a slide-actuating mechanism adapted to mark port contours in succession.

2

Therefore, the device according to the invention enables the automatic generation of ports of variable dimensions and in diverse spaced relationships along the tube by means of nibbling said tube with a single punch which insures very close tolerances in the size and spacing of the ports punched.

The invention is described hereinafter, by way of example, with reference to the accompanying drawing, in which:

FIG. 1 shows a longitudinal section of the device according to the invention;

FIG. 2 is a section taken along line A—A in FIG. 1;

FIG. 3 is a section taken along line B—B in FIG. 1;

FIG. 4 is a cross-sectional view of the punch for producing the smallest size port;

FIG. 5 is a development of the surface of a tube with ports of various shapes generated by means of a single punch according to the present invention;

FIG. 6 shows diagrammatically the means whereby synchronized operation of the mechanisms for longitudinal motion and rotation of the tube is effected with the slide actuating mechanism; and

FIG. 7 shows a portion of FIG. 1 on enlarged scale.

Referring to FIG. 1, a tube 1 is placed in the clearance defined between a hollow mandrel-die 2 and a cage 3. The mandrel-die is mounted at one end on a cantilever quill 4 fixed in a bracket 5 which is secured on a plate 6.

A press frame 7 with the cage 3 mounted thereon is fixed to the plate 6. The cross section of the punch 8 (see FIG. 2) corresponds to the minimum size port to be cut, the punch being mounted on a slide 9 of the press. The slide 9 and the punch 8 are driven in reciprocating motion with a frequency preferably of 1,000 strokes per minute, whereby ports of various shapes and size can be nibbled by a single punch in this manner.

The press slide 9 with the punch 8 fixed thereon is set in motion by means of a toggle mechanism 10 mounted in frame 7 which, in turn, is actuated by an eccentric shaft 11 also mounted in frame 7 and driven by an electric motor 12.

During reciprocation of the press slide, the tube 1 is shifted in a longitudinal direction or rotated in respect to the die by a nibbling pitch t (FIG. 4) which is less than the size a of punch 8. The motion of tube 1 in the direction of arrow C is timed with the reciprocating motion of the punch in such a manner that successive portions of tube 1 are fed under the punch for the nibbling of ports of a given shape.

Scrap or waste in the form of small punchings drops through the die opening into space b of die 2 and is discharged by compressed air, while any waste which does not drop into space b is removed during the longitudinal motion of the tube.

The longitudinal motion of the tube is carried out by means of a feed screw 13, a nut 14 and a carriage 15 (see FIG. 1) travelling on ball-type guide ways 16, and carrying a work-holding device comprising the spring-loaded holding fixtures 17, which are caused by a nut 18 with a tapered inner surface, which clamp the tube by means of holes provided in the tube near its end.

The nut 18 is threadably connected with a sleeve 19 assembled in bearings 20 and 21 of the carriage 15. A pinion 22 is rigidly fitted on the sleeve 19 and is in mesh with a gear wheel 24 which is keyed on a feed shaft 23 of the tube turning mechanism. Thus, the tube turning mechanism is adapted for turning the tube around its axis, whereby the tube can be both rotated and longitudinally displaced.

After the contour of port 25 has been nibbled or punched, the feed motion of the tube under the punch for nibbling the next port 26 is carried out without stopping the slide 9 and the punch fixed in the latter. For

this purpose, a wedge-acting device is provided on the upper part of the press frame 7 for the displacement of the slide from its operative position, this device being connected with a bearing-block support 27 and toggle mechanism 10. The bearing-block support 27 is constantly urged to an upper inoperative position by springs 28 which urge the block 27 to the top wall of the frame. A wedge 29 is slidably supported on the bearing block 27 and is connected to the piston of a pneumatic cylinder 30. When compressed air is admitted into the cylinder 30, its piston pushes the wedge 29 along an inclined surface of the bearing-block 27. This causes the wedge 29 to lower the bearing-block 27 until it is thrust against the shoulders 31 of the frame 7. In this position the press slide 9 and the punch 8 are in their lower operative position. When compressed air is evacuated from the pneumatic cylinder 30, the spring 32 returns the piston and wedge 29 to their initial inoperative position until the block 27 will contact the shoulder of the frame 7. This causes the return of the toggle mechanism 10, the slide 9 and the punch 8 to their initial inoperative position all under the action of spring 28. Simultaneously the rotary and longitudinal feed motion of the tube for nibbling the next port is effected.

The operation of the pneumatic cylinder 30 of the wedge mechanism is controlled by a slide valve air distributor actuated by a solenoid (not shown in the drawings) which receives command signals from a control unit according to a given program (not shown).

The tube feed motion during the period of port nibbling is synchronized with the reciprocating motion of the punch 8 in such a way that feeding of the tube for a nibbling pitch is performed only during the idle stroke of the punch. To assure such synchronization the lengthwise feed mechanism and the tube turning mechanism are provided with torque hydraulic boosters 33 and 34 respectively (see FIGS. 1 and 6), which are controlled by step servomotors 35 and 36 (FIG. 6). Output shafts 37 and 38 of hydraulic boosters 33 and 34 are respectively coupled with feed screw 13 and feed shaft 23.

The shafts (not shown in the drawings) of step servomotors 35 and 36, and therefore screw 13 and feed shaft 23, are caused to rotate when the windings of these servomotors are supplied with electric pulses D continuously produced by blocking generator 39 mounted in the control panel.

In order to make tube 1 perform movements timed with those of punch 8, cam shaft 11 carries a pickup 40 (FIGS. 1 and 6), for instance, of a photoelectric type for recording angular position. The pickup closes the respective electric circuit, whose signal indicated by arrowhead E (FIG. 6) open electric valve 41 passable to pulses produced by blocking generator 35 during the no-load travel of the punch.

As a result, the winding of servomotors 35 and 36 are supplied in accordance with a predetermined program through the commutating blocks 42 and 43 of the servomotors, with only a certain portion of pulses to cause rotation of the servomotor shafts through a certain value in correspondence with the nibbling pitch t.

Hydraulic boosters 33, 34 and 41 are powered by a common hydraulic pump 44 (arrowheads F and G).

It should be noted that the embodiments described above and illustrated in the drawings are but preferable variants of the present invention.

Variations may be made in the form, size and arrangement of the components. The above-described units can

be, for instance, substituted for their equivalents, the location of individual components can be changed, and some units can be employed independently of the others. However, all these variations are considered to be within the concept and scope of the invention if defined in the accompanying claims.

What we claim is:

1. A device for forming ports in a thin-walled tube, comprising a plate with guideways therein; a frame mounted on said plate; a slide in said frame for having a punch secured therein, said punch having a cross-section corresponding to the size of the smallest port to be formed in the tube; means in said frame to drive said slide in reciprocation; a driven cam shaft in said frame coupled to the latter means to drive the same; a bracket mounted on said frame; a mandrel die having one end secured in said bracket; a cage accommodating the other end of said mandrel die and spaced therefrom by a clearance, said cage being mounted on said frame and said clearance serving for the accommodation of a tube therein; a carriage supported for travelling in said guideways of the plate and including means for clamping the tube in which the ports are to be formed; a mechanism for moving the tube lengthwise including a feed screw having one end mounted in said frame and an opposite end in said bracket and a nut secured in said carriage and engaged with the feed screw for being driven thereby; a mechanism for turning the tube and including a feed shaft having one end secured in said frame and an opposite end in said bracket and having kinematic connection with said means which clamps the tube; and means for synchronizing the operation of said mechanism which lengthwise feeds the tube and the mechanism which turns the tube and the means which drives the slide in reciprocation to effect the forming of the outline of the ports in the tubes.

2. A device according to claim 1, comprising means serving to withdraw the slide from an operative position to an inoperative position without stopping said cam shaft and comprising a displaceable wedge, a spring-urged support for said wedge and coupled to said means which drives the slide in reciprocation, and a power cylinder arranged on said frame and coupled to the wedge for displacing the same.

3. A device as claimed in claim 1 wherein said clamping means comprises a sleeve provided with radial openings and secured in said carriage, a coupling nut mounted in said sleeve and having a tapered inner surface, and spring-urged members extending through said radial openings of the sleeve and gripping the tube with their lower ends as the upper ends of said members cooperate with said tapered surface of the coupling nut.

4. A device as claimed in claim 1 wherein said mechanisms which feed the tube lengthwise and turn the tube include respective motors, torque boosters for said motors, and servomotors controlling said boosters.
